UNITED STATES PATENT OFFICE

DANIEL W. MACMILLAN, OF PROVIDENCE, RHODE ISLAND, ASSIGNOR TO MACMILLAN & CO., INC., OF PROVIDENCE, RHODE ISLAND, A CORPORATION OF RHODE ISLAND

MULTIPLE MACHINE

Application filed November 19, 1929. Serial No. 408,316.

The present invention relates to multiple machines for operating on a continuous strip of stock material, and has particular reference to multiple machines of the eyelet type.

5 One object of the invention is to provide a novel feeding mechanism and a novel feeding method for a multiple machine with a plurality of sets of tools operating on a single strip of stock material.

10 Another object of the invention is to provide a feeding arrangement for the strip of stock material which will relieve all stress and pull on the strip between successive operations.

15 A further object is to provide independent feeding mechanisms for each set of tools.

An additional object is to feed the strip of stock material so as not to conceal or interfere with the operations, and not to affect 20 the accessibility of the tools for adjustment or replacement.

With these and other objects in view, the invention consists of a novel arrangement of parts more fully disclosed in the detailed 25 description following, in conjunction with the accompanying drawings, and more particularly set forth in the appended claims.

In the drawings:

Figure 1 is a front elevation of the novel 30 multiple machine;

Figure 2 is a back elevation thereof;

Figure 3 is a section on the line 3—3 of 35 Figure 2, showing the path of travel of the strip of stock material, and the feeding mechanism therefor; and

Figure 4 is an enlarged sectional detail of a guide block for the stock strip.

It has been found desirable, in the use of 40 multiple tool machines operating on a continuous stock strip, to eliminate all stress and pull on the strip between successive operations and thus permit exact work centering without distortion; and it has been found of 45 advantage to provide feeding devices which do not obstruct the vision of the operator and do not interfere with adjustment or replacement of tools. I have devised a novel feeding arrangement which feeds the strip stock in a helical loop around the lower portion of the 50 machine to be operated upon by the tools in

successive passes in sequence or independently, as desired, the slack in the depending loop portions eliminating all stress and pull on the work and I utilize positive intermittent feeds to feed each strip stock portion to the next tool, thus insuring exact alignment of the work and tool irrespective of the number of operations performed in the multiple machine; and the following is a detailed description of the specific embodiment of my invention as applied to a multiple drawing, cutting or swaging machine of the eyelet type:

Referring to the drawings, 10 designates the frame of the multiple machine, comprising a head section 11, a bed section 12, and the usual support members or feet 13. A plurality of independently operating tools 14 are mounted to reciprocate in the head section guide ways 15, and are actuated in timed relation by a cam or crank shaft 16 rotated through the pulley drive 17. Each operating tool 14 has a cooperating die block or the like 18 which is firmly positioned in alignment therewith on the bed section 12, both the operating tool and die block being adjustable and replaceable in the usual manner.

The stock strip 19 is of the continuous strip type and is preferably drawn off a supply 50 roll 20 journaled on the frame 10, the stock strip passing around the bed section in a helical curve for successive presentation to the tool sets. As is particularly shown in Figure 3, the strip stock passes upwardly between two spaced guide rods 21—22, over a rounded guide block 23 and under a retainer guide wire 24 and into engagement with a die block 18; the strip stock then passes through a guide bar 25 and over a curved front plate 26 to again pass between guide rods 21, 22.

Each tool set is equipped with an independent feeding device 27; the illustrated device comprises a spring pressed pivoted lever 55 28 having an adjustable roller arm 29 at one end thereof adapted to be actuated by a cam 30 in timed relation to the movement of its set of cooperating tools, a feeder and holder finger 31 or the like being pivotally mounted 60

on the lower end to engage the work strip under tension of the usual spring 32 for successively feeding the work strip forward to its set of cooperating tools. Instead of using 5 a finger device as described above, a pinch feed such as shown at 33 in Figure 2, may be used, the finger type being preferable for eyelet and punch operations.

Depending on the nature of the work, the 10 die block may be provided with an ejector of any well known type to permit free advance of the stock strip after each operation, this device being omitted from the drawings to simplify the illustration thereof.

15 My improved feeding arrangement therefore feeds the work, progressively to the tool sets without obstructing the vision of the operator and without diminishing the accessibility of the tools for adjustment or replacement; in addition, the slack of the depending loop portions permits positive free feeding to each tool set, which feeding may be entirely independent of the other adjacent feedings. Preferably, the tools are operated in succession upon the same material, and may, if desired, be operated independently or in unison, the feeding mechanisms being arranged to cooperate with the timed movement of the associated tools.

20 The intermittent feeding to each tool set may be in unison, but preferably is in timed relation to the operation of each tool set, and slightly displaced in time phase, thus being out of time with each other to reduce excessive vibration. The tool sets may be adjusted to obtain a sequence of operations for producing a single article, or to operate independently, as desired.

25 While I have described a specific embodiment of my invention, it is obvious that desired changes in arrangement and in the construction of the parts may be made without departing from the spirit and the scope of the invention as defined in the appended 30 claims.

I claim:

1. In combination, a machine frame, a series of tools movably mounted therein for operating on a continuous strip of stock, 35 means for guiding the stock in a substantially helical path in successive passes to be operated upon by said series of tools, and means for positively feeding said stock to each tool.

2. In combination, a machine frame, a series of tools movably mounted therein for successively operating on a continuous strip of stock, means for guiding the stock in a substantially helical path in successive passes 40 to be operated on by said series of tools, and independent means for feeding said stock to each tool.

3. In combination, a machine frame having a head section and a bed section, a series 45 of cooperating tool sets mounted in said sec-

tions for operating on a continuous strip of stock, and means for guiding said continuous strip in a substantially helical path in successive passes around said bed section and through said series of tools.

4. In combination, a machine frame having a head section and a bed section, a series of cooperating tool sets mounted in said sections for successively operating on a continuous strip of stock, and means for guiding said continuous strip in a substantially helical path in successive passes around said bed section and through said series of tools. 70

5. In combination, a machine frame having a head section and a bed section, a series of cooperating tool sets mounted in said sections for operating on a continuous strip of stock, means for guiding said continuous strip in a substantially helical path in successive passes around said bed section to be operated upon by said series of tools, and means for positively feeding said strip to each tool set. 80

6. In combination, a machine frame having a head section and a bed section, a series of cooperating tool sets mounted in said sections for successively operating on a continuous strip of stock, means for guiding said continuous strip in a substantially helical path in successive passes around said bed section to be operated upon by said series of tools, and independent means for positively feeding said strip to each tool set. 90

7. In combination, a machine frame having a head section and a bed section, a series of cooperating tool sets mounted in said sections for operating on a continuous strip of stock, means for guiding said continuous strip in a substantially helical path in successive passes around said bed section to be operated upon by said series of tools, and independent means for positively feeding said strip to each tool set at predetermined time intervals. 100

8. In a multiple punch press, a frame having a head section and a bed section, a series of punches mounted in said head section, a series of cooperating dies mounted in said bed section, and means for guiding a continuous strip of stock in a substantially helical path in successive passes around said bed section to be operated upon by said series of cooperating punches and dies. 110

9. In a multiple punch press, a frame having a head section and a bed section, a series of punches mounted in said head section, a series of cooperating dies mounted in said bed section, means for guiding a continuous strip of stock in a substantially helical path in successive passes around said bed section to be operated upon by said cooperating series of punches and dies, and means for positively feeding said strip to each set of cooperating punches and dies. 120

10. In a multiple punch press, a frame having a head section and a bed section, a series of punches mounted in said head section, a series of cooperating dies mounted in said bed section, means for operating sets of cooperating punches and dies in succession, and means for guiding a continuous strip of stock in a substantially helical path in successive passes around said bed section to be operated upon by said sets of punches and dies. 75
11. In a multiple punch press, a frame having a head section and a bed section, a series of punches mounted in said head section, a series of cooperating dies mounted in said bed section, means for operating sets of cooperating punches and dies in succession, means for guiding a continuous strip of stock in a substantially helical path in successive passes around said bed section to be operated upon by said series of punches and dies, and independent means for positively feeding said strip to each set of cooperating punches and dies in timed relation to their operation. 80
12. In combination, a machine frame, a series of reciprocating tools movably mounted therein for operating on a continuous strip of stock, means for guiding the stock in a substantially helical path in successive passes to be operated upon by said series of tools, and means for positively feeding said stock to each tool. 85
13. In combination, a machine frame, a series of reciprocating tools movably mounted therein for successively operating on a continuous strip of stock, means for guiding the stock in a substantially helical path in successive passes to be operated on by said series of tools, and independent means for feeding said stock to each tool. 90
14. In a multiple punch press, a frame having a head section and a bed section, a series of punches mounted in said head section, a series of cooperating dies mounted in said bed section, mechanism for operating the cooperating punches and dies, guiding devices for guiding a continuous strip of stock in a substantially helical path in successive passes to be successively operated on by said series of punches and dies, and feeder finger mechanism for positively feeding said strip to each set of cooperating punches and dies in timed relation to their operation. 95
15. In a multiple punch press, a frame having a head section and a bed section, a series of punches mounted in said head section, a series of cooperating dies mounted in said bed section, mechanism for operating the cooperating punches and dies at intervals which are relatively displaced in phase, guiding devices for guiding a continuous strip of stock in a substantially helical path in successive passes to be successively operated on by said series of punches and dies, and feeder finger 105

mechanism for positively feeding said strip to each set of cooperating punches and dies in timed relation to their operation.

In testimony whereof I affix my signature.

DANIEL W. MacMILLAN.
